UNITED STATES PATENT OFFICE.

HERMAN G. MUELLER, OF ERIE, PENNSYLVANIA, ASSIGNOR TO SKINNER ENGINE COMPANY, OF ERIE, PENNSYLVANIA, A CORPORATION OF PENNSYLVANIA.

STEAM ENGINE.

Application filed April 3, 1921. Serial No. 459,610.

In operating steam engines difficulty is experienced in maintaining the most effective and desirable compression where there is a variable back-pressure on the exhaust. With 5 the present invention the volume of steam compressed is varied so as to control the compression. It is also desirable to vary the compression in relation to the supply pressure. The supply pressure ordinarily does 10 not vary greatly so that a change with relation to it is not as important, perhaps, as the variation due to changes in the back-pressure yet it affords an advantage and the present invention accomplishes this result.

15 The invention is illustrated in the accompanying drawings as follows:—

Fig. 1 shows a side elevation of an engine, partly in section.

Fig. 2 a horizontal section of the engine.

20 Fig. 3 a section on the line 3—3 in Fig. 1.

1 marks the cylinder, 2 the piston operating in the cylinder, 3 the steam supply pipe supplying steam through the ordinary poppet valves 4, the valves receiving their motion from a lay shaft 5 through bell cranks 5^a operating on the valve stems 5^b. An exhaust system comprises an exhaust port 6 which is arranged in the center of the cylinder, the engine shown being of the unafow type and auxiliary exhausts which are preferably supplied at 7, these being controlled by the usual valves at 7^a. It will be understood that the valves at 7^a close in the usual manner during the power stroke but are open 25 during the exhaust stroke so the compression follows the cut-off afforded by the port 7. It will be understood, however, that the exhaust system may comprise only the ports 6 in the usual manner of central exhaust unafow engines if desired.

40 In order to control the compression with a varying exhaust I prefer to provide a varying clearance which varies automatically as the compression varies so as to control it and to have the supply pressure a factor in this control so that variations in the supply pressure will also have a response in the variations in clearance. Clearance cylinders 8 are connected by ports 9 with the ends of 45 the cylinder 1. Pistons 10 are arranged in the cylinders 8. Stems 11 extend from the pistons 10 through the glands 12, these stems being preferably provided with the graduations 13 to indicate the position of the piston. 50 Pipes 14 lead from the cylinders 8 to a com-

mon chamber 15. The chamber 15 is connected by a pipe 16 with each one of the passages 17 connected with the supply so that the chamber 15 is under supply steam pressure at all times. The chamber 15 is preferably partially filled with oil, this oil extending through the pipes 14 into the ends of the cylinders 8. Valves 18 are arranged in the pipes 14, these valves being of the plug valve type having the plugs 19 with 55 ways 20. Stems 21 extend from the plugs 19. Rock arms 22 are arranged on the stems 21 connected by links 23 with the rock arms 24 on the lay shaft.

60 In the operation of the present device the valve 18 at the same end of the cylinder as the piston is opened through the action of the lay shaft and the connecting link 23 on the return stroke of the piston just prior to the moment the piston reaches its extreme 65 position. The valves 18 are closed approximately at the point of cut-off. The pressure which is delivered on the pistons 10 and the chamber 8 from the cylinder side, that is, the effective pressure, is the mean pressure 70 of the cylinder during the time the pressures are opposed on the pistons 10. It will be noted that the pistons will take any position necessary to maintain the proper clearance 75 space. During the period that the piston 10 is thus subjected to the cylinder pressure the opposite face of the piston is subjected to supply pressure by reason of the opening of the valve 18. It will be noted that the piston 80 is of greater area on its surface subjected to the cylinder pressure than on the surface subjected to the supply steam pressure through the pipe 14 by reason of the area of the stem 13. This difference represents the 85 difference in the cylinder pressure with a 90 normal back-pressure and supply pressure. If there is an abnormal back-pressure this 95 will result in an abnormal compression, which being communicated to the cylinder 8 will move the piston 10 outwardly thus increasing the portion of the cylinder 8 in communication with the ends of the cylinder and forming a part of the clearance space. This outward change will be in the nature 100 of a series of outward movements until 105 equilibrium is established. On the other hand if the back-pressure should be reduced so that the added clearance is so great as to reduce the compression below what it should be this lower compression will be felt in the 110

cylinders 8 and the preponderance of supply pressure will move the piston 10 inwardly reducing the clearance space. It will be noted that as the clearance is varied by the variation of the location of the piston in the cylinder 8 the volume of steam compressed is varied and that the initial compression clearance space is also varied and that this variation is in proportion to the variations in back pressure. Again if the supply pressure should be increased so as to make a higher compression desirable this preponderance of supply pressure over the compression of the moment will move the pistons 10 inwardly reducing the clearance and bringing the compression to a point that will afford an equilibrium with the supply pressure. In this way the compression is controlled automatically.

20. What I claim as new is:—

1. In a steam engine, the combination of a power cylinder having an exhaust system cutting off the exhaust for compression; a power piston in the cylinder; clearance chambers connected with the cylinder at its ends; clearance varying pistons in the chambers varying the capacity of the chambers in connection with the power cylinder; and means controlling said clearance varying pistons at the initial compression for varying their position as the exhaust back-pressure varies.

2. In a steam engine, the combination of a power cylinder having an exhaust system cutting off the exhaust for compression; a power piston in the cylinder; clearance chambers connected with the cylinder at its ends; clearance varying pistons in the chambers varying the capacity of the chambers in connection with the power cylinder; and means controlling said clearance varying pistons at the initial compression for varying their position as the supply steam pressure varies.

45. 3. In a steam engine, the combination of a power cylinder having an exhaust system cutting off the exhaust for compression; a power piston in the cylinder; clearance chambers connected with the cylinder at its ends; clearance varying pistons in the chambers varying the capacity of the chambers in connection with the power cylinder; and means controlling said clearance varying pistons at the initial compression for varying their position as the supply steam pressure and exhaust back pressure varies.

40. 4. In a steam engine, the combination of a power cylinder having an exhaust system cutting off the exhaust for compression; a power piston in the cylinder; clearance chambers connected with the cylinder at its

ends; clearance varying pistons in the chambers varying the capacity of the chambers in connection with the power cylinder, said pistons having differential faces, the larger 65 face being subjected to the power cylinder pressure and the smaller face to supply steam pressure; a valve gear for the engine; and means acting with said valve gear controlling the action of the supply steam on 70 the clearance varying pistons.

5. In a steam engine, the combination of a power cylinder having an exhaust system cutting off the exhaust for compression; a power piston in the cylinder; clearance 75 chambers connected with the ends of the cylinder; clearance varying pistons in the clearance chambers; liquid connections leading from said clearance chamber; liquid in said connections; means for subjecting the 80 liquid to supply steam pressure; valves in the liquid connection; a valve gear for the engine; and means acting with the valve gear controlling said valves.

6. In a steam engine, the combination of 85 a power cylinder having an exhaust system cutting off the exhaust for compression; a power piston in the cylinder; clearance chambers connected with the ends of the cylinder; clearance varying pistons in the 90 clearance chambers; liquid connections leading from said clearance chamber; liquid in said connections; means for subjecting the liquid to supply steam pressure; valves in the liquid connections; a valve gear for 95 the engine; means acting with the valve gear controlling said valves; and stems extending from said clearance varying pistons to without the chamber and reducing the 100 effective area of the pistons.

7. In a steam engine, the combination of a power cylinder having an exhaust system cutting off the exhaust for compression; a power piston in the cylinder; clearance chambers connected with the ends of the 105 cylinder; clearance varying pistons in the clearance chambers; liquid connections leading from said clearance chamber; liquid in said connections; means for subjecting the liquid to supply steam pressure; valves in 110 the liquid connections; a valve gear for the engine; means acting with the valve gear controlling said valves; and stems extending from said clearance varying pistons to without the chamber and reducing the 115 effective area of the pistons, said stems having graduations indicating the position of the clearance varying pistons.

In testimony whereof I have hereunto set my hand.

HERMAN G. MUELLER.
